Walter W. Davison

By

Clarence S. Walker
Attorney

UNITED STATES PATENT OFFICE.

WALTER W. DAVISON, OF BUFFALO, NEW YORK, ASSIGNOR TO WIRE WHEEL CORPORATION OF AMERICA, OF BUFFALO, NEW YORK, A CORPORATION OF NEW YORK.

WHEEL.

Application filed March 19, 1920. Serial No. 367,074.

To all whom it may concern:

Be it known that I, WALTER W. DAVISON, a citizen of the United States, and resident of Buffalo, Erie County, State of New York, ⁵ have invented certain new and useful Improvements in Wheels, of which the following is a specification.

This invention relates to an improvement in wire wheels and particularly to locking ¹⁰ means for use therewith.

One object of this invention is to provide a detachable wheel with a plurality of locking means which operate simultaneously.

Another object of this invention is to increase ¹⁵ the number of locking positions of a hub cap without changing the fastening means formerly employed.

Other objects will appear from an examination of the specification and drawing ²⁰ which forms part thereof and in which,

Fig. 1 is a transverse section and

Fig. 2 is a section taken along the line 2.

Referring to the drawings, 10 and 11 designate the inner hub and hub shell respectively of a detachable wheel. The hub shell 11 is held in position by a hub cap 12 which is threaded on to the inner hub 10 and bears at its periphery against the hub shell. ²⁵

Mounted in grooves 13 and 14 on the inner face of the hub cap are locking bars 15 and 16 which, as shown, are adapted to engage the hub shell in a manner to be described later. In the outer face of the hub cap is provided a wrench receiving groove 17 into ³⁰ which one end of each locking bar projects so that the bars will be retracted when the wrench is inserted in the groove. This construction is fully disclosed in Patent No. 1,324,513 to George E. Molyneaux and since ³⁵ it forms no part of this invention no further description is believed necessary.

The outer ends of the bars are provided with lock-engaging portions 18 and 19 which extend through openings 20 and 21 in the side of the hub cap. Springs 22 and 23 which pass through holes in the bars 15 and 16 respectively act to hold the portions 18 and 19 in operative position. ⁴⁰

Mounted in the mouth of the hub shell ⁴⁵ 11 is a locking ring 24 which is provided with a plurality of equally spaced slots 25. The portions 18 and 19 under the influence

of the springs 23 and 24 tend to enter the slots and hold the hub cap in place when the wrench is removed from the groove 17. ⁵⁵

It will be noted however, that the divisions 26 between the slots 25 must take the strain should there be any tendency to loosen the hub cap. For that reason the divisions are made of appreciable width, and it is not possible to tighten the cap a small amount although it is desirable to have the shell held firmly in place on the inner hub. ⁶⁰

This result might be obtained by increasing number of slots in the ring 24 but this would mean reducing the width of the divisions 26 and necessarily weakening them. I have, however, increased the number of locked positions without weakening the locking by the following means: the locking bars 15 and 16 are so arranged that the portions 18 and 19 enter the slots 25 simultaneously thus doubling the number of locking positions. The number of locking bars could of course be increased if desired ⁷⁰ without departing from the spirit and scope of my invention. ⁷⁵

Having thus described my invention, what I claim and desire to secure by Letters Patent is:—

1. In a wheel, the combination with an inner hub of a hub shell mounted thereon, a hub cap on said hub and bearing against said hub shell to hold it on said hub, a locking ring fixed in the mouth of said hub shell and provided with a series of equally spaced slots, the division between said slots being of substantially the same width as the slots, a plurality of locking bars mounted in said hub cap and normally tending to reciprocate ⁸⁵ radially therein into engagement with the slots in said ring to lock positively the cap against loosening, said bars being so located that when one is in engagement with a slot in the locking ring another rests against a ⁹⁰ division in the ring. ⁹⁵

2. In a wheel, the combination with an inner hub of a hub shell mounted thereon, a hub cap on said hub and bearing against said hub shell to hold it on said hub, a locking ring fixed in the mouth of said hub shell and provided with a series of equally spaced slots, the division between said slots being of substantially the same width as the slots, a ¹⁰⁰

locking bar mounted in said hub cap and normally tending to reciprocate radially therein to engage a slot in said ring, and the engaging portion of said bar being beveled on one side so that the bar when in the slot positively prevents loosening of the hub cap under all conditions of the wheel but permits tightening and a second locking bar mounted to reciprocate radially in said hub

cap, said second bar engaging a division 10 between the slots when the first bar is in a slot, and having its engaging portion beveled on one side similar to the first named bar so that when the hub cap is tightened first one locking bar and then the other locking bar engages a slot in the hub shell. 15

In testimony whereof I affix my signature.

WALTER W. DAVISON.
